CLAIM

The ornamental design for a multicompartment compact, as shown and described.

DESCRIPTION

FIG. 1 is a perspective view of a compact showing our new design;

FIG. 2 is a top plan view thereof;

FIG. 3 is a front elevational view thereof;

FIG. 4 is a rear elevational view thereof;

FIG. 5 is a side elevational view thereof;

FIG. 6 is a bottom plan view thereof; and

FIG. 7 is an exploded perspective view of our design showing the compact in an opened condition.

FIG.1

FIG.2

FIG.3

FIG.4

FIG.5

FIG.6
